UTENSIL LID

Natalie de Lebecque, Beverly Hills, Calif.

Application August 1, 1952, Serial No. 20,874

Term of patent 14 years

(Cl. D44—15)

To all whom it may concern:

Be it known that I, Natalie de Lebecque, a citizen of the United States of America, residing in the city of Beverly Hills, county of Los Angeles, State of California, have invented a new, original, and ornamental Design for a Utensil Lid, of which the following is a specification, reference being had to the accompanying drawing, forming a part thereof.

The essential features of the design reside in the portions shown in full lines. The drawing is shaded to illustrate contrasting appearance.

I claim:

The ornamental design for a utensil lid, substantially as shown and described.

NATALIE DE LEBECQUE.
